UNITED STATES PATENT OFFICE.

SAMUEL P. GAVER, OF EWING, NEBRASKA, ASSIGNOR OF ONE-HALF TO
REASON CONNOR, OF SAME PLACE.

CAR-COUPING.

SPECIFICATION forming part of Letters Patent No. 372,371, dated November 1, 1887.

Application filed April 17, 1886. Renewed September 3, 1887. Serial No. 248,730. (No model.)

To all whom it may concern:

Be it known that I, SAMUEL P. GAVER, a citizen of the United States, residing at Ewing, in the county of Holt and State of Nebraska, 5 have invented certain new and useful Improvements in Railroad - Couplers and Bumper-Heads; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 This invention has relation to improvements in car-couplers; and it consists in the construction, novel arrangement, and adaptation of devices, as will be hereinafter more fully set forth and claimed.

20 In the accompanying drawings, Figure 1 is a side view of a draw-head with parts broken away, showing the pin in a set position. Fig. 2 is a side view showing the link in position therein. Fig. 3 is a view of the slide removed. 25 Fig. 4 is a view of one of the connecting-links, and Fig. 5 is a vertical longitudinal sectional view.

Referring by letter to the said drawings, A indicates a draw-head, which may be of any 30 suitable construction, and provided with the inwardly-inclined recess *a* in the lower wall of its mouth to seat the weighted end of the connecting-link, so as to hold the opposite end thereof in an elevated position for the introduction of the same into the draw-head of a 35 meeting car.

Passing vertically through the mouth of the draw-head is the pin-aperture *b*, and at the 40 roof of the said mouth in the lateral walls are internal grooved ways, C C, for the reception of the slide D. This slide is provided with an annular aperture, which is adapted to coincide with the pin-aperture in a vertical plane when the said slide is pushed in and partially close the same and form a temporary 45 rest for the pin when drawn out. Communi- 50 cating with the annular aperture of the slide D is a slot, *d*, through which a pin in the roof of the draw-head projects and forms a stop to limit the outward movement of the said slide.

Upon the upper side of the draw-head is

fixed a vertical forked standard, E, and between the branches of this standard is pivoted a vibrating lever, F, the forward end of which is pivotally connected with the upper end of 55 the coupling-pin by means of a link, *e*. Exterior to this vibrating lever, and by means of its pivot-rod *g*, is connected to the standard E a weighted bail or lever, G, which is designed to vibrate the lever F and raise and lower the 60 coupling-pin.

While I have shown and described a bail for this purpose, yet it is obvious that a single pivoted lever may be used.

In operation, when it is desired to couple a 65 car with another carrying a link, the bail should first be thrown rearward upon the lever F, which will cause the pin to rise to its fullest extent. The slide should then be drawn, so as to allow the pin to rest thereon, and the 70 position of the bail reversed, so as to engage the opposite end of the vibratory lever. When the meeting car strikes the slide, the same will be pushed in and the pin dropped through the slot of the link, thereby making the connection. When it is desired to uncouple, it is 75 only necessary to throw the link back upon the vibratory lever, when the pin will be raised.

Having described this invention, what I claim is—

1. The combination, with the draw-head constructed as described and provided with the grooved ways in its lateral walls, of the slide arranged in said grooves and having a slot for a stop-pin, and an annular aperture adapted 85 to coincide with the pin-aperture, the pin pivotally connected to an oscillating lever, and the swinging bail exterior to the said lever, substantially as specified.

2. The combination, with the draw-head 90 having the pin-aperture and the bifurcated standard, of the vibratory lever pivoted to the said standard, the pin pivotally connected with the forward end of the said lever, and the swinging bail or lever exterior to the said vibratory lever, substantially as specified.

In testimony whereof I affix my signature in presence of two witnesses.

SAMUEL P. GAVER.
